UNITED STATES PATENT OFFICE.

EZEKIEL VAN NOORDEN, OF BOSTON, MASSACHUSETTS.

METALLIC SHINGLE.

SPECIFICATION forming part of Letters Patent No. 341,188, dated May 4, 1886.

Application filed January 2, 1886. Serial No. 187,381. (No model.)

To all whom it may concern:

Be it known that I, EZEKIEL VAN NOORDEN, of Boston, in the county of Suffolk and State of Massachusetts, a citizen of the United States, have invented a new and useful Improvement in Metallic Shingles, of which the following is a full, clear, and exact description, reference being had to the accompanying drawings, forming a part of this specification in explaining its nature.

The invention relates to a metallic shingle having strengthening-ribs disposed in relation to each other as hereinafter described, means for securing the shingles to each other and in a manner to provide a water-tight construction, and in water-guards arranged along the edges of the shingles, as hereinafter specified.

Referring to the drawings, Figure 1 represents in perspective a portion of a roof partially covered with my shingles. Fig. 2 is a section, enlarged, on the dotted line $x-x$ of Fig. 1. Fig. 3 is a section, enlarged, on the dotted line $y-y$ of Fig. 1. Fig. 4 is a perspective view of a single shingle. Fig. 5 is a cross section of a single shingle upon the dotted line of Fig. 4. Fig. 6 is a detail view.

The shingles preferably are square in form and are made from tin or other suitable sheet metal; but they are secured to the roof with the point A uppermost. Each shingle has its edge a between the lines or points 1 2 and its edge b between the points 3 4 turned upward to form a water-guard, and it also has at its upper corner the rounded or dish-shaped recess or cavity a' in its under surface, formed by striking up the section a^2 of the shingle or metal plate. The cavity preferably is circular in plan. At the right corner of the shingle is another recess or cavity, a^3 , which is half-round—that is, it is formed to extend to the edge a^4 of the plate—as represented in Fig. 4, and a portion of the metal forming this recess or cavity is cut or struck up to form a fastening extension or finger, a^5 . At the left corner of the shingle, upon a line with the cavity a' , is another recess or cavity, a^6 , formed by striking up the metal of the shingle, which is similar in shape to the one last described, with the exception that its opening extends to the edge a^7 of the shingle, and it likewise has a fastening extension or finger, a^8 , formed by

striking up or slitting the metal of the shingle, as represented. At the lower corner of the shingle there is also a recess or cavity, a^9 , formed by striking up the metal, which is half the size of the cavity last mentioned, and which embraces the entire lower corner of the shingle. It has a hole, a^{10} , formed therein by cutting a slit across the same and slightly depressing one surface adjacent thereto. There is arranged to extend from the recess or cavity a' to the recess or cavity a^3 , parallel with its edge, the bead or rib b , which forms a cavity, b' , upon the under surface of the shingle. A bead or rib, b^2 , forming a cavity, b^3 , also connects the recess or cavity a^2 with the cavity a^6 , parallel with the side edge, b^4 . The two recesses or cavities a^6 a^9 are connected with each other by a bead or rib, b^5 , formed immediately adjacent to the edge, which provides a cavity or recess, b^6 .

The recess or cavity a' and the recess or cavity a^3 are connected by a bead or rib, b^7 , also formed adjacent to the edge a^4 , which provides a recess or cavity, b^8 , in the under surface. There is also formed in the shingle the bead or rib c , which extends parallel with the edge a^1 from the point 5 to the point 6, and forms a recess or cavity, c' , and the bead or rib c^2 , which extends from the end of the rib c , parallel with the side edge, a^1 , to the point 7 and forms the cavity c^3 . These ribs or beads are disposed in relation to each other to accomplish two purposes—first, to provide a water-tight construction by the overlapping of the margins of the shingles, as hereinafter described; and, second, to strengthen them.

In joining the shingles together the upper corner having the full recess or cavity a' comes uppermost in each shingle, and the next shingle to the right thereof has its side edge, a^7 , overlapping, so that the side water-guard, a , enters the cavity c' and the rib b^7 the edge cavity, b^5 , and the cavity a^6 fits upon the imperforate rounded upper end of the shingle. The next shingle, or the one to the left, is arranged so that its edge a^1 extends or overlaps upon the edge of the first shingle, and so that the water-guard b^4 of the lower shingle extends into the cavity c^3 of the other shingle, and the rib or bead b^2 of the lower shingle is covered by the rib or bead b^7 . The next or fourth shingle has

its lower end, a^9 , resting upon the section a^3 of the third shingle in order.

- It will be seen that the shingles as finally arranged are of four thicknesses at the corners and of two thicknesses along the intermediate overlapping edges or sections, and that at each corner the first or undermost part is the section a^2 , that the corner of the next section in order rests thereon and has the finger or fastening projection a^5 , which extends upward therefrom through the hole formed by making the fastening projection a^8 , that the next shingle in order also has a fastening projection or finger, a^8 , which extends through the hole a^{10} in the uppermost shingle, and which may also receive the finger or fastening-extension of the second shingle in order, and that the corners of the shingles are thereby firmly fastened or secured together.
- Of course in lieu of fastening fingers formed by striking up or cutting the metal of the shingle itself, I may use independent or separate fingers or fastenings secured by solder, or by riveting to the shingles, and adapted to be used substantially as are the fingers described, with the exception that there would be but one used on each shingle, and it would be arranged to extend through holes formed in the corners of the other two, similar to the hole in the lower corner of the shingle. By this construction the shingles are firmly secured together, and a continuous double water-guard formed about each shingle, and the shingle is at the same time strengthened by the ribs and edges which make or form the water-guards.

Of course nails or solder, or both, may be used, either with or without the fastenings above described, for securing the shingles together and to the roof.

- In some instances, to provide additional stiffness or strength, the fingers a^5 a^8 are provided with lengthwise corrugations, as shown in Fig. 6.

There may be used in lieu of the fingers

cleats of metal fastened to the roof to project 45 over the overlapping corners a^8 a^6 and adapted to enter the hole a^{10} .

Having thus fully described my invention, I claim and desire to secure by Letters Patent of the United States—

50

1. A metal shingle having the imperforate section a^2 , forming the cavity a' , the beads or ribs b b^2 , extending therefrom and providing the cavities b' b^3 , and the corner recesses or cavities a^3 a^6 a^9 , the beads or ribs b^3 b^4 , connecting 55 them, forming the cavities b^6 b^9 , all substantially as described.

2. A metal shingle having the struck-up imperforate section a^2 , forming a cavity, a' , the beads or ribs b b^2 , extending therefrom and 60 forming the cavities b' b^3 , the recesses or cavities a^3 a^6 a^9 , formed in the corners thereof, as specified, the connecting edge beads or ribs b^5 b^7 , forming the edge cavities b^6 b^9 , the beads or ribs c c^2 , forming the cavities c' c^3 , and the 65 turned-up side edges, a b^4 , all substantially as described.

3. A metal shingle having the upper recess or cavity, a' , and the cavities a^3 a^6 a^9 at or near the corners, and shaped substantially as specified, and the fastening finger or fingers a^5 a^8 , 70 all substantially as described.

4. The metal shingle having the cavity a' , formed as described, the beads or ribs b b^2 , extending therefrom and forming the cavities 75 b' b^3 , the water-guards a b^4 , the fingers a^5 a^8 , and the hole a^{10} , substantially as described.

5. The combination of a shingle having the raised imperforate section a^2 , the raised corner section a^6 , the bead or rib b^2 , and the water-guard b^4 , with a shingle having the raised sections a^3 a^9 and the ribs c^2 b^7 , forming the cavities c^6 b^9 , all substantially as described.

EZEKIEL VAN NOORDEN.
